UNITED STATES PATENT OFFICE.

GEORGE H. DAY, OF ROCHESTER, NEW YORK, ASSIGNOR TO AMERICAN OPTICAL COMPANY, OF SOUTHBRIDGE, MASSACHUSETTS, A VOLUNTARY ASSOCIATION OF MASSACHUSETTS.

TEMPLE.

1,271,020.

Specification of Letters Patent. Patented July 2, 1918.

Application filed April 11, 1918. Serial No. 227,884.

To all whom it may concern:

Be it known that I, GEORGE H. DAY, a citizen of the United States, residing at Rochester, in the county of Monroe and 5 State of New York, have invented certain new and useful Improvements in Temples, of which the following is a specification.

This invention relates to new and useful improvements in temples and more particularly to a division of my original application which was filed September 13, 1917, Serial No. 191,176, and has particular reference to an improvement in that type of temple which is formed from metal and xylonite 15 or a similar non-metallic material so united that they will be securely held against any disconnection.

Another object of the present invention is the provision of an improved manner of 20 uniting the various parts so as to present a neat and attractive structure to rigidly and firmly unite the parts and prevent any liability of breakage at the joint by reinforcement of the more brittle non-metallic member.

A still further object of the invention is the provision of a joint wherein the metallic and non-metallic parts are engaged with each other in such a manner that they will 30 be securely and satisfactorily held against movement and at the same time provide a finished article which will be braced or reinforced so as to prevent any liability of breakage at the joint.

With the above and other objects in view the invention consists in the novel features of construction and the combination and arrangement of parts hereinafter more fully set forth, pointed out in the claims, and 40 shown in the accompanying drawings, in which—

Figure I is a side elevation of a temple constructed in accordance with my invention:

Fig. II is a detailed enlarged elevation, parts thereof being broken away and illustrated in longitudinal section:

Fig. III is a similar view taken at right angles to the showing in Fig. II:

Fig. IV is a detailed enlarged view of the exterior of the joint illustrating the same in elevation: and

Fig. V is an enlarged longitudinal sectional view illustrating a modified form of 55 the invention.

Referring now more particularly to the drawings in which the reference characters designate the several parts throughout the views, the numeral 1 indicates the metallic side of a temple and 2 the non-metallic part or loop thereof, said loop being provided at its inner end with a slot or kerf as illustrated at 3, the inner end of which is provided with an inclined wall 4, said wall terminating at one end in a transverse portion 5 which provides a suitable stop for the inner end of the metallic temple 1 when the end of the temple is inserted within the slot or kerf 3.

The end of the temple piece 1 which is connected with the ear loop 2 is provided with an enlarged flattened portion 6 having formed therein a transverse opening 7 and having its outer end provided with an inclined wall coincident with the wall 4 and further provided with a transverse portion 8 adapted to contact with the portion 5 to form a stop when the end 6 is inserted within the slot of the ear loop 2.

In connecting the two parts of the temple together, the end 6 of the metallic part 1 is inserted within the slot 3 of the non-metallic portion and the coengaging parts are then heated to a certain degree and pressed tightly together so that the non-metallic portion, which is preferably of xylonite, hard rubber, or other similar material, will coengage with the opening 7 and other parts of the metallic portion 1 to assist in retaining the parts against longitudinal movement.

In order to firmly unite the two sections and provide for a neat appearance to the joint, a ferrule 9 is provided and adapted to be engaged over the joint and extend upon the non-metallic portion to a point beyond the inner end of the metallic portion 1, and formed therein is a circumferential indentation 10 which is forced therein by applying pressure to this point of the ferrule and serves not only to bite into the non-metallic part 2 but to provide additional means whereby the two parts of the temple are firmly united. It will be noted that by applying pressure to the ferrule to form the indentation 10, it will force the material of the non-metallic portion 2 into the opening 7 as is clearly illustrated in Fig. III. From this it will be apparent that after the above operation has been carried out, the two parts of the temple will be securely united against 110

any movement with respect to each other, and as the ferrule is placed upon the joint before the material has cooled, it will be apparent that portions of the material will 5 be readily forced into the opening 7 so as to provide a firm connection between the two portions of the temple.

In Fig. V I have illustrated a slightly modified form of the invention wherein the 10 non-metallic part 2 is provided with a kerfed end and the metallic part 1 is provided with an enlarged longitudinal head portion 11 having a longitudinal slot 12 formed therein which is adapted to receive the material 15 of the non-metallic part 2 when the same is pressed tightly over the end 11 so as to securely hold the two parts against movement. Furthermore, this form of the invention is provided with the ferrule 9 having the indentation 10 therein which provides additional means for forcing the material of 20 the loop 2 into the opening 12.

It will be apparent from the foregoing description taken in connection with the 25 accompanying drawings that I have provided a neat and attractive temple constructed of metallic and non-metallic parts which are securely united together and are provided with means whereby the connecting ends 30 thereof are securely held against any relative movement with respect to each other.

I claim:

1. The combination with a non-metallic ear hook having a kerfed end, of a metallic 35 temple side having one end engaged within the kerfed end of the ear hook, a ferrule arranged over the joint, and means whereby the ferrule is secured against movement and at the same time forces the material of the 40 ear hook into engagement with the end of the metallic temple side whereby to prevent relative movement of the ear hook and temple side.

2. The combination with a non-metallic 45 ear hook, having a slot in one end, of a metallic temple side, having a slot in one end thereof, said slotted end being adapted to be engaged within the slot in the ear hook to form a joint, a ferrule arranged over the 50 joint, and means whereby the ferrule is secured against movement and at the same time forces the material of the ear hook into the slot at the head of the temple side.

3. The combination with an ear hook, having a slot in one end thereof, of a temple 55 side, a flattened head of the temple side

adapted for insertion into the slot in the ear hook, said head having a slot therein, a ferrule arranged over the joint formed by the engaged ends of the temple sides and ear 60 hook, and a beading formed on the interior of the ferrule for retaining the temple side and ear hook against movement.

4. The combination with a non-metallic ear hook, having a slot in one end extending 65 longitudinally of the end of the hook, of a metallic temple side, a flat head on one end thereof having a slot therein, said head being adapted to be engaged within the slot of the ear hook and having its edges flush with the outside of the body of the ear hook, and a ferrule arranged over the meeting ends of the temple side and ear hook and bearing against the sides of the head to securely hold the parts against lateral movement.

5. The combination with a non-metallic ear hook having a slot in one end extending longitudinally of the end of the hook, of a metallic temple side, a flat head on one end thereof having a slot therein, said head being adapted to be engaged within the slot of the ear hook and having its edges flush with the outside of the body of the ear hook, a ferrule arranged over the meeting ends of the temple side and ear hook and bearing 85 against the sides of the head, said ferrule being forced inwardly into the non-metallic material of the ear hook thus forcing the material into the head of the temple side to hold the joint against movement.

6. The combination with a non-metallic ear hook having a kerfed end, of a metallic temple side having one end engaged with the kerfed end of the hook and means whereby the metallic member is coengaged with the 95 non-metallic member to prevent longitudinal movement of the same.

7. The combination with an ear hook, having a slot in one end thereof, of a temple side, a flattened head on the temple side adapted for insertion into the slot in the ear hook, said head having a slot therein to receive portions of the ear hook to retain the ear hook and temple side against longitudinal movement.

In testimony whereof I have affixed my signature, in presence of two witnesses.

GEORGE H. DAY.
